Patented Aug. 23, 1921.

INVENTOR.

R. E. Perkins

BY
Watson E. Coleman

ATTORNEY.

UNITED STATES PATENT OFFICE.

RICHARD E. PERKINS, OF BOSTON, MASSACHUSETTS.

RAZOR.

1,388,598.

Specification of Letters Patent. Patented Aug. 23, 1921.

Application filed September 4, 1920. Serial No. 408,171.

To all whom it may concern:

Be it known that I, RICHARD E. PERKINS, a citizen of the United States, residing at Boston, in the county of Suffolk and State 5 of Massachusetts, have invented certain new and useful Improvements in Razors, of which the following is a specification, reference being had to the accompanying drawings.

- 10 This invention relates to certain improvements in razors and has relation more particularly to a device of this general character of a safety type, and it is primarily an object of the invention to provide a device of 15 this character with novel and improved means whereby the cutting blade is caused to vibrate as the device makes a working stroke and wherein the blade is of a double cutting edge type.
- 20 Another object of the invention is to provide a novel and improved device of this general character embodying a cutting blade adapted to reciprocate or vibrate during a shaving stroke and wherein the razor is of a 25 type whereby the same may be manipulated in the same manner as the old fashioned flat blade razor.

The invention consists in the details of construction and in the combination and arrangement of the several parts of my improved razor whereby certain important advantages are attained and the device rendered simpler, less expensive and otherwise more convenient and advantageous for use, 35 as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view partly in top plan and partly in section illustrating a razor constructed in accordance with an embodiment 45 of my invention.

Fig. 2 is an enlarged view partly in front elevation and partly in section of the razor as herein disclosed with the handle fragmentarily shown in full open position.

50 Fig. 3 is a sectional view taken substantially on the line 3—3 of Fig. 2.

Fig. 4 is a view in end elevation of the device as herein embodied.

Fig. 5 is a view in top plan of the guard member as herein embodied, the shank carried thereby being shown in fragment.

Fig. 6 is a view in plan of the blade as herein embodied.

Fig. 7 is a view in plan of the blade carrier herein employed, and 60

Fig. 8 is a detail sectional view taken substantially on the line 8—8 of Fig. 1.

As disclosed in the accompanying drawings, 1 denotes an elongated guard member preferably oblong and which is provided along its opposite longitudinal margins with the guards 2 of a conventional type. The central portion of the member 1 is provided with an elongated and relatively broad opening or slot 3, the central portion of the longitudinal edge of said slot being provided with the supplemental notch or recess 4. 65

One end portion of the member 1 has integrally formed therewith an elongated shank 5 to the outer or free end portion of 75 which is pivotally engaged, as at 6, a bone handle 7 of a well known type and which, in the present instance, is employed to facilitate the proper and easy holding of the device during a shaving operation. As is particularly indicated in Fig. 2, the major portion of the shank 5 is of double thickness. 80

The end portion of the member 1 with which the shank 5 is engaged is provided at opposite sides of said shank with the upstanding lugs 8 while the opposite end portion of the member 1 is provided with the upstanding flange 9 provided adjacent its opposite ends with the inwardly directed lips or tongues 10. 85

11 denotes a blade carrier which overlies the guard member 1 and said blade carrier 11 has its central portion provided with the elongated opening or slot 12 with the ends of said slot or opening defined by the downwardly disposed flanges 14. The blade carrier 11 is of a length less than the member 1 and the flanges 14 are spaced apart a distance less than the longitudinal axis of the opening or slot 3 so that when the blade carrier 11 is in applied position, the same 95 is capable of reciprocation. The flanges 14 extend through the slot or opening 3 and substantially snugly engage therein, whereby the slot or opening 3 serves as a guide 100 for the blade carrier 11 whereby the blade carrier 11 has vibration in substantially a fixed path of travel. 105

A longitudinal margin of the blade carrier 11 defining the opening or slot 12 is provided with a depending arcuate wing 15 110 which, when the blade carrier 11 is applied, extends through the opening or slot 3 and

the lower or free end portion of said wing 15 is provided with an upstanding pin 16 for a purpose to be hereinafter more particularly referred to.

5 A cutting blade C is adapted to be interposed between the guard member 1 and the blade carrier 11 and the central portion of said cutting blade C is provided with the elongated opening or slot 17 through which 10 the flanges 14 also extend, said flanges and end edges of the blade C being in contact so that the blade carrier 11 and the blade C will be caused to reciprocate or vibrate in unison. The blade C is of a double edge 15 type and of such width to permit the blade to be used in connection with either of the guards 2.

The notch or recess 4 is provided to facilitate the proper passage of the wing 15 20 through the slot or opening 3 and for which reason it is also desired that the width of the slot or opening 17 be substantially equal to the width of the slot or opening 3 plus the depth of the notch or recess 4. The marginal portions of the blade C defining the ends of the opening or slot 17 are provided with the notches or recesses 18 in which the flanges 14 snugly engage so that the blade C is effectively held against any transverse 25 movement independently of the blade carrier 11 which would otherwise interfere with the efficiency of the device.

19 denotes a clamping plate which is adapted to overlie the applied blade carrier 11 and one end portion of the plate 19 is provided in its upper surface with the recesses or notches 20 which receive the lips or tongues 10 hereinbefore referred to. The opposite end portion of the plate 19 has 30 close contact with the inner faces of the lugs 8. Said end portion of the plate 19 between the lugs 8 is provided with a short shank 21 which overlies and contacts with the inner or adjacent end portion of the shank 5 and in order to facilitate or assure 35 such contact, the inner portion of the short shank 21 is inwardly or downwardly offset, as at 22.

Slidably mounted on the shank 5 is a 40 sleeve 23 which, when at the limit of its inward movement, embraces both the shank 5 and the short shank 21 and has contact with the shoulder afforded by the offset 22. By this means, the clamping plate 19 and 45 the remaining parts of the device are effectively held or retained in working assembly.

The central portion of the plate 19 is provided with an elongated opening or slot 24 provided at its opposite ends with the up- 50 standing ears 25. The ears 25 provide mountings for a journal rod 26. Loosely mounted on the rod 26 and snugly fitting between the ears 25 is a roller 27. This roller 27 extends through the openings or 55 slots 17, 12 and 3 so that the pin 16 here-

inbefore referred to may be properly engaged within the cam groove 28 provided in the periphery of the roller 27 and extending circumferentially therearound.

The periphery of the roller 27 is serrated 70 or otherwise roughened so that as the razor is drawn across the face with the roller 27 in contact therewith, said roller will rotate and at the same time reciprocate or vibrate the blade carrier 11 and the blade C so that 75 the cutting of the hair is materially facilitated.

Under certain conditions, it is of advantage that the cutting blade C be held against vibration or reciprocation and particularly 80 when it is desired to shave the upper lip in close proximity to the nostril. As herein disclosed, the roller 27 is held against rotation by a catch 29 carried by the clamping plate 19 which engages within one of the 85 circumferentially spaced notches or recesses 30 formed in the periphery of the roller 27. The notches or recesses 30 are spaced apart a distance whereby, when the catch 29 is engaged in one of said notches or recesses 90 30, the blade C will be positively held at the limit of its reciprocatory movement in one direction. This is of importance in view of the fact that an end of the blade C will be sufficiently extended to materially 95 facilitate the shaving of the upper lip in close proximity to the nostril.

From the foregoing description it is thought to be obvious that a razor constructed in accordance with my invention is 100 particularly well adapted for use by reason of the convenience and facility with which it may be assembled and operated, and it will also be obvious that my invention is susceptible of some change and modification 105 without departing from the principles and spirit thereof and for this reason I do not wish to be understood as limiting myself to the precise arrangement and formation of the several parts herein shown in carrying out my invention in practice except as hereinafter claimed.

I claim:

1. A razor of the class described comprising a guard member provided with a slot, 115 a blade carrier overlying said guard member and also provided with a slot, a blade interposed between the guard member and the blade carrier, said blade being provided with a slot, a clamping member overlying 120 the blade carrier and engaged with the guard member, a wing carried by the blade carrier and extending through the slots of the blade and guard member, a roller carried by the clamping member, said clamping member being provided with a slot through 125 which the roller extends, and coacting means carried by the wing and the roller whereby the blade carrier is reciprocated upon rotation of the roller.

2. A razor of the class described comprising a guard member provided with an elongated slot, a blade carrier overlying said guard member and also provided with an elongated slot, a blade interposed between the guard member and the blade carrier, said blade being provided with an elongated slot, the blade carrier adjacent the opposite ends of the slot therein being provided with flanges extending through the slots in the blade and the guard member, said flanges contacting with the end edges of the slot in the blade, a clamping member overlying the blade carrier and engaged with the guard member, and coacting means carried by the clamping member and the blade carrier for imparting reciprocation to the blade carrier during a shaving stroke.
3. A razor of the class described comprising a guard member provided with an elongated slot, a blade carrier overlying said guard member and also provided with an elongated slot, a blade interposed between the guard member and the blade carrier, said blade being provided with an elongated slot, the blade carrier adjacent the opposite ends of the slot therein being provided with flanges extending through the slots in the blade and the guard member, said flanges contacting with the end edges of the slot in the blade, a clamping member overlying the blade carrier and engaged with the guard member, a wing carried by the blade carrier and extending through the slots of the blade and guard member, a roller carried by the clamping member, said clamping member being provided with a slot whereby said roller extends through the clamping member and the blade carrier, and coacting means carried by the wing and the roller whereby the blade carrier is reciprocated upon rotation of the roller.
4. A razor of the class described comprising a guard member provided with a slot, a blade carrier overlying said guard member and also provided with a slot, a blade interposed between the guard member and the blade carrier, said blade being provided with a slot, a clamping member overlying the blade carrier and engaged with the guard member, a wing carried by the blade carrier and extending through the slots of the blade and guard member, a roller carried by the clamping member, said clamping member being provided with a slot through which the roller extends, coacting means carried by the wing and the roller whereby the blade carrier is reciprocated upon rotation of the roller, and means for holding the roller against rotation.
5. A razor of the class described comprising a guard member, a blade carrier overlying said guard member, a blade interposed between the guard member and the blade carrier, a clamping member overlying the blade carrier and engaged with the guard member, a roller carried by the clamping member, a wing carried by the blade carrier and partially overlying the roller, and coacting means carried by the roller and the wing whereby the blade carrier is reciprocated upon rotation of the roller.
6. A razor of the class described comprising a guard member, a blade carrier overlying said guard member, a blade interposed between the guard member and the blade carrier, a clamping member overlying the blade carrier and engaged with the guard member, a roller carried by the clamping member, a wing carried by the blade carrier and partially overlying the roller, coacting means carried by the roller and the wing whereby the blade carrier is reciprocated upon rotation of the roller, and means for holding the roller against rotation.
7. A razor of the class described comprising a guard member, a blade carrier overlying said guard member, a blade interposed between the guard member and the blade carrier, a clamping member overlying the blade carrier and engaged with the guard member, a roller carried by the clamping member, a wing carried by the blade carrier and partially overlying the roller, coacting means carried by the roller and the wing whereby the blade carrier is reciprocated upon rotation of the roller, and means carried by the clamping member and engageable with the roller for holding the roller against rotation.

In testimony whereof I hereunto affix my signature.

RICHARD E. PERKINS.
